ATTORNEY.

UNITED STATES PATENT OFFICE.

EDMOND MOLLOY, OF PHILADELPHIA, PENNSYLVANIA, ASSIGNOR TO JOHN F. MOLLOY
AND RICHARD T. MOLLOY, BOTH OF PHILADELPHIA, PENNSYLVANIA.

SIGN-BOARD.

1,267,340.

Specification of Letters Patent. Patented May 21, 1918.

Application filed July 17, 1916. Serial No. 110,599.

To all whom it may concern:

Be it known that I, EDMOND MOLLOY, a citizen of the United States, residing at Philadelphia, in the county of Philadelphia and State of Pennsylvania, have invented certain new and useful Improvements in Sign-Boards, of which the following is a specification.

Advertising sign boards of the length used 10 when they are placed beside railroads, and motor traveled roads, heretofore have been solid structures, erected on solid foundations, and solidly braced to withstand the wind pressure. This bracing was usually 15 made by a slanting timber set at various points along the panel of the sign board, which unless they did not extend above the bottom of the panel, marred its appearance, and made it impossible to use to its full advantage 20 the side of the sign board on which they were placed.

My present device is intended to avoid the necessity for this heavy and solid construction, by making the panel a light truss structure, swinging on supports when the pressure of the wind becomes great so that it will present a sloping surface, or even, in a very high wind, its edge to the wind. The lumber used in a sign board of the former 30 construction, blown down for lack of strength to withstand wind pressure, will often be sufficient to furnish all the material for one of my construction and leave nearly half of the lumber of the old sign unused, 35 and yet the new sign board will withstand much greater wind pressure than destroyed the sign board of the former construction. This swinging panel is very advantageously 40 usable with movable supports, such as herein described and many other advantages of the within described form of sign board will be pointed out or will be seen readily from the description in the following portions of the specification.

Figure 1 is a side elevation of the sign board. Fig. 2 is a section on line $x-x$ of Fig. 1. Fig. 3 is an enlarged view of the end of a panel with the facing removed. Fig. 4 shows the base of the support, the supporting timbers being cut on line $y-y$ of Fig. 1. Fig. 5 is an enlarged view of the trunnion on which the swinging panel turns. Fig. 6 is a plan view showing the auxiliary truss. Fig. 7 is a view of a different form of support. Fig. 8 is a side elevation of a different

form of panel adapted to a curved top, and Fig. 9 a detail of the auxiliary truss.

The panel is a sheathed truss. The bent members 2 and 3 are bellied downward. The string piece 4 lies above. The curved members are made of a number of strips, and fastened together by nails or other instrumentalities, and laid over each other in layers, the pieces breaking joints. By making these curved members belly downward, they 65 tend to retain their shape, and the concave form of the truss framework dispenses with the need for diagonal struts, ties and braces, such as would be required in other forms of truss construction. This truss structure can 70 be made of very light material and the omission of struts and braces tends still further to lighten it. The curved elements, 2, and 3 and the stringer are connected together at their ends and extend to the end of 75 the panel in practice. The sheathing or facing 7, 7, can be placed on one or both sides of the parts 2, 3, 4, and the bottom may if desired extend below the piece 30 and be finished by framing pieces 6 that, 80 when both sides of the truss are sheathed may extend from one face to the opposite face. This sheathing will amply suffice to make the truss structure rigid, and keep the panel always in shape, especially in view of 85 the downward curves given to the elements 2 and 3.

The auxiliary truss placed at the upper side of the panel gives rigidity in a direction substantially at right angles to the 90 height of the panel and prevents the panel and the stringer piece 4 from buckling. The truss height of this auxiliary truss is at a substantial angle, preferably nearly at a right angle with the truss height of the 95 main truss. This auxiliary truss is very light and very cheap and simple in its construction. This auxiliary truss consists of compression members, 10, 10, crosswise of the panel, provided with diagonal tension 100 members, 11, 11. These tension members, 11, 11, are in practice wires which are suitably secured by a bolt or a staple to the ends of the compression members, 10, 10, giving the crosswise turn around the staple or bolt 105 if need be to keep it from slipping, and thence carrying it across the top of the panel to the opposite side of the next compression member, to which it is drawn taut, secured and then continued diagonally across the top 110

of the panel to the next piece 10, and so on to the end of the truss. These wires are in practice secured not only to each other where they cross but also to the top of the 5 panel (though a sufficient rigidity will often be given if only secured to each other or to the panel) so as to give absolute rigidity to the truss. These wires, in time, often become stretched, I can take them up by 10 stapping them together by staples 13, 13, (see Fig. 9). In this figure is shown also, at the right, a slightly different arrangement of the wires. In the very right of the figure the wires are shown as returning to the end 15 of the next compression member, on the same side of the panel and returning after having taken a turn around the wire from the opposite ends of the compression members. This turn is designated by the ordinary 20 17. 16, 16, denote staples securing the wires to the top of the panel. The plank 18 is preferably secured to the top of the panel, and to it the compression members, which in practice are wooden strips, are secured. 25 This construction obviates any chance of the parts 10, becoming detached from the panel, especially if the plank 18 is a little wider than the thickness of the panel. The panel is supported through the shoulders 22, 22, 30 formed in practice of a number of shoulder pieces, fitting at one end against the truss member 3, and preferably extending upward, to the level of the stringer 4. The panel can swing on a trunnion 21 formed by 35 mortising the lowest of these shoulder pieces. The points of support for the panel are above its center of gravity, so that it will swing freely back into a perpendicular position when the air is still. The area of 40 the surface of panel below its points of support, however, should be materially greater than that above so that the air pressure will swing it readily. The form of truss structures shown and described makes most of 45 the weight lie near the top of the panel so that the supporting points can be high without being much above the center of gravity. The bearings of the panel on which it swings are in practice placed a short distance from 50 the ends of the panel, both better to distribute the weight and to make the supports less prominent. The trunnion 21 is placed near the bow piece 3, and a space 26 made in the panel where it can clear the standard 30 55 as the panel swings.

The standards 30 for the panel are placed beneath the trunnions. In practice these are two inclined timbers 31, 31, having a seat 35 at the top to receive the trunnion. These 60 timbers are connected together at the bottom by a plank 36. A horizontal floor 34, 34 formed of boards is built beneath the standard 30, preferably being nailed or bolted to the plank 36. The upwardly extending 65 boards 38, 38, and 37, 37 are secured to the

horizontal floor 34, 34, and to each other, the boards 38, 38, being preferably inclined inward and secured to the sloping timbers 31, 31 of which the standards are constructed in practice. This construction gives a broad 70 flat base for the standard 30, serves as a receptacle 33, to contain earth stone or other ballast, and enables the sign to be erected without digging and on marshy ground.

Another form of standard is shown in 75 Fig. 7, where an upright pipe 40 is screwed into a star 41 into which are screwed the sectional pieces of pipe. The star and the pieces of pipe can be sunk a short distance below the surface of the ground or weighted. 80 The top of pipe 40 is provided with a T 43 and a hole is bored in the shoulder piece and a rod or pipe pushed through it and through the T.

Fig. 8 shows a form of panel where the 85 top is curved, a bent truss member 50, rises above the panel and has on it an auxiliary truss 51. In this form of panel the stringer piece can either be retained or omitted as seems best.

In any form of panel, a single concave truss element only can be used if rigidity enough is secured by it. Therefore, either the element 2 and the element 3 can be omitted under such circumstances. The ends of 95 the compression pieces, 10, 10, form convenient supports for lamps, 117, 117, (shown diagrammatically merely by circles) which illuminate the signs and, when the panel is swaying, give a particularly attractive appearance.

The sign can be painted on the sheathing 7 of the panel or nailed to it, or can even, where only one side of the panel is sheathed, 105 be pinned over the truss elements and the back of the sheathing or can be attached to it.

The whole structure most conveniently is constructed from lumber where the sign is to be placed, or the material brought to that 110 place "knocked down." The elements 2 and 3 can be built by pegging out their shape in the ground, and bending and securing together the strips to form them, within the pegs, the stringer 4 is then put in place, 115 and enough sheathing is secured to the truss pieces to hold them in place. The standards are built and put in place, the panel mounted on them, as can readily be done since the truss structure without the sheathing of the 120 panel is very light and the rest of the sheathing fastened on. The auxiliary truss can be built on the ground when the plank is used, and can be mounted on the panel after the latter is in place. As is readily seen, no 125 special kinds of material, or special tools are required, for the sign board, or in its construction.

I claim:

1. In a sign board a swinging panel 130

- formed of a sheathed truss having a plurality of the truss elements that extend lengthwise of the truss, provided with bearings above the center of gravity of the panel and having the greater area of the panel below the bearings, and standards provided with seats for the bearings of the panel upon which the swinging panel swings on the standards.
- 5 10. 2. A sign board having in combination a swinging panel provided with a truss running lengthwise of the panel and having a braced truss structure with its truss height substantially at right angles with the swing-
- 15 ing panel, standards for the swinging panel and bearings on which the swinging panel swings on the standards.
- 10 3. A sign board having in combination a truss structure having a plurality of the truss elements that extend lengthwise of the truss covered with a facing forming a swinging panel, standards for the panel, bearings placed on the panel above the center of gravity but substantially below the top 25 of the panel and seats for the bearings, placed on the standards.
- 20 4. A sign board having a swinging panel provided with a truss structure, consisting of downwardly bellied bow pieces, and a longitudinal stringer piece at the upper part 30 of the panel, and having this truss structure covered by a flat facing.
- 25 5. The combination in a swinging panel sign board, of a swinging panel having trunnions on which to swing, standards placed beneath these trunnions and having seats to receive them, a floor at the bottom of the standards and side planking extending upward at the sides of the floor the floor the 35 planking and standards being mutually secured together.
- 30 6. The combination in a swinging panel sign board, of a swinging panel, having trunnions on which to swing, standards placed beneath these trunnions and having seats to receive them, a floor at the bottom of each standard, side planking extending upward from the floor, the side planking, standard and floor being permanently secured together and two opposite sides of the 45 side planking being inclined inwardly toward the standard and secured thereto.
- 40 7. In sign boards, the combination with the
- standard and the swinging panel, composed of a truss structure covered with sheathing 55 and provided with an auxiliary truss composed of compression pieces running crosswise to the panel and diagonal tension members.
- 5 8. In sign boards the combination with the standards and a swinging panel formed of a sheathed truss structure, of an auxiliary truss formed of compression pieces extending crosswise of the panel and wire diagonal tension members secured to the 65 ends of the compression members and to the panel between the compression members.
- 10 9. In a sign board having a swinging panel, an auxiliary truss placed on the top of the panel, consisting of a plank extending 70 lengthwise of the panel and the compression members running crosswise to the plank and secured to same and wire tension members, running from the compression members to the plank between the compression mem- 75 bers.
- 15 10. In a sign board the combination of a swinging panel consisting of a sheathed truss having a plurality of the truss elements that extend lengthwise of the truss 80 and standards placed near the ends of the sheathed truss and swingingly supporting the truss.
- 20 11. In a swinging sign board, the combination with the supporting standards of a 85 panel consisting of a main truss of sheathing on same, and of an auxiliary truss rigidly secured to the main truss and having the truss height of the auxiliary truss at a substantial angle with the truss height of 90 the main truss.
- 25 12. A sign board having in combination a swinging panel provided with a truss running lengthwise of the panel, and having a plurality of truss elements running length- 95 wise of the truss, and having also a braced truss structure running lengthwise of the panel with its truss height substantially at right angles with the height of the panel, and consisting of a lengthwise piece, com- 100 pression members running crosswise of the truss structure, and diagonal tension members.

In testimony whereof I affix my signature.

EDMOND MOLLOY.
